UNITED STATES PATENT OFFICE

THOMAS E. HERRICK, JR., OF PHILADELPHIA, PENNSYLVANIA

CYLINDER STRUCTURE

Application filed January 29, 1929. Serial No. 335,827.

The invention relates to certain improvements in three-cylinder locomotives, in which one cylinder is located between the side frames of the locomotive and the other cylinders mounted on the outside of said frames.

The object of my invention is to so construct the locomotive that a deep frame can be used to which the cylinder structures are rigidly secured, and to perforate the frame for the passage of exhaust steam from the outside cylinders to the passages in the central cylinder structure.

In the accompanying drawings:

15 Fig. 1 is a transverse sectional view through the cylinders and frames of a three-cylinder locomotive;

20 Fig. 2 is a side view, with one of the side cylinders removed;

25 Fig. 3 is a detached view of one of the side cylinders;

Fig. 4 is a side view of the front portion of one of the side frames; and

30 Fig. 5 is a plan view of the frame shown in Fig. 4.

In the accompanying drawings, 1—1 are the side frames of the locomotive, spaced a given distance apart and made as shown in Figs. 4 and 5.

35 Located between the side frames is the central cylinder structure 2, and located on the outside of one of the frames is a cylinder structure 3, while on the opposite side is the cylinder structure 3^a. In the present instance all three cylinders are high pressure cylinders.

The central cylinder structure 2 has a cylinder 4 preferably inclined as shown in Fig.

40 1. The valve-chest 5 of this cylinder forms an integral part of the central structure 2 and has an inlet passage 6 arranged to be coupled to a high pressure steam pipe. The valve-chest is cylindrical and has the usual 45 bushings and ports. Passages 7 lead to and from the end of the cylinder 4 and exhaust passages 8 lead from the valve-chest to an exhaust passage 9, which is formed around the underside of the cylinder 4 and leads 50 to the nozzle 10 which opens into the smoke-

box of the locomotive directly under the stack in the usual manner.

The central cylinder structure 4 has flanges 11 which rest upon the side frames and has the usual saddle 12 which is cast integral with 55 said structure.

The side cylinder structures 3—3^a are identical in form, with the exception that one is a left-hand cylinder structure and the other is a right-hand cylinder structure. In each 60 structure is a cylinder 13 and a cylindrical valve-chest 14. Ports 15 connect the valve-chest with both ends of its cylinder, and each valve-chest has an inlet port 16.

Exhaust passages 17 lead from the valve-chest to passages 18 in the side frames of the locomotive, shown clearly in Figs. 1 and 2. In the present instance the exhaust passages 17 of the left-hand cylinder structure 3 communicate with the exhaust passage 9 in the 65 central cylinder structure 2, while the exhaust passages 17 of the right-hand cylinder communicate through the passages 18 in the frame with exhaust passages 19 which 70 open into the main exhaust passage 9 some 75 distance from the frame as shown in Fig. 1. Each side cylinder structure has lugs 20 which rest upon the upper edge of its frame.

The side frames are made as shown in Figs. 4 and 5, being of considerable depth at the 80 cylinder structures as at 21, having vertical lugs 22—22 between which the cylinder structures are mounted. Keys 23 are driven between the lugs and each cylinder structure, giving a long and rigid bearing for said 85 structure.

The frames extend beyond the lugs and 90 form bumper supports 24. The frames are reduced in depth at this point to clear the truck wheels, Fig. 2.

Each cylinder structure is flanged, and securing bolts pass through openings 25 in the flanges and openings 26 in the side frames, firmly securing all the cylinder structures to the frames, and as the frames are of considerable depth at this point, a very rigid 95 construction results.

By making the passages 18 in the side frames, the exhaust passages are comparatively straight.

While I have described my invention as applied to a three-cylinder high pressure locomotive, in some instances the central cylinder may be omitted and a central structure may be used having only the exhaust passage, nozzle and saddle, or the central cylinder may be a high pressure cylinder and the side cylinders low pressure cylinders, without departing from the essential features of the invention.

10 I claim:—

- 15 1. The combination in a locomotive of the three-cylinder type, of two side frames having exhaust passages therein; a central cylinder structure mounted between the frames and having an integral cylinder; an exhaust passage formed in the central cylinder structure, said exhaust passage extending under and around one side of the central cylinder, and having openings aligning with the passages in the two frames; a side cylinder on each side of the structure, one mounted on the outside of one frame and the other mounted on the outside of the other frame, and having exhaust passages communicating with the passages in the frame of the locomotive, whereby the exhaust from the said side cylinders passes through the frames and through the central cylinder structure.
- 20 2. The combination in a locomotive of the three-cylinder type, of two side frames, each having an exhaust passage therein; two side cylinder structures having flanges secured to the outside of the side frames, the cylinder
- 25 portions of the cylinder structures extending below the lower edges of the side frames, and having exhaust passages communicating with the exhaust passages in the side frames; a central cylinder structure secured to the inner sides of the said side frames, and having an inclined cylinder located entirely above the lower edges of the frames; exhaust passages in the central structure extending under and around one side of the cylinder, and communicating with the exhaust passages in the frames.
